COMBINED GEARSHIFT LEVER AND HOUSING FOR AUTOMOBILES

Robert G. T. Reilly, 13652 Yorba St.,
Tustin, Calif. 92680

Filed Dec. 28, 1970, Ser. No. 26,663

Term of patent 14 years

Int. Cl. D12—16

U.S. Cl. D14—6

FIG. 1

FIG. 5

FIG. 2

FIG. 1 is a perspective view of a combined gearshift lever and housing for automobiles, showing my new design;

FIG. 2 is an enlarged top plan view thereof;

FIG. 3 is a side elevation thereof;

FIG. 4 is a rear elevation thereof;

FIG. 5 is a horizontal section taken on line 5—5 of FIG. 1; and

FIG. 6 is a fragmentary bottom plan view thereof.

I claim:

The ornamental design for a combined gearshift lever and housing for automobiles, substantially as shown.
